US00D613554S

(12) **United States Design Patent**
Koennecke

(10) **Patent No.:** **US D613,554 S**
(45) **Date of Patent:** **** Apr. 13, 2010**

(54) **CUP**(75) Inventor: **Weston Koennecke**, Oak Park, IL (US)(73) Assignee: **Solo Cup Operating Corporation**, Lake Forest, IL (US)(**) Term: **14 Years**(21) Appl. No.: **29/305,200**(22) Filed: **Mar. 14, 2008**(51) **LOC (9) Cl. .... 07-01**(52) **U.S. Cl. .... D7/509; D7/523**(58) **Field of Classification Search** D7/523, D7/509, 500, 396.2, 387, 392.1; 215/387, 215/DIG. 7; 220/703, 592.16, 592.17; 229/400; D9/744, 751, 434

See application file for complete search history.

FOREIGN PATENT DOCUMENTS

DE 1175564 8/1964

(Continued)

Primary Examiner—Robert M Spear*Assistant Examiner*—Cynthia Underwood(74) *Attorney, Agent, or Firm*—Banner & Witcoff, Ltd.(57) **CLAIM**

The ornamental design for a cup, as shown and described.

DESCRIPTION

FIG. 1 is a perspective view showing our new design of a cup;

FIG. 2 is a front view thereof;

FIG. 3 is a left view thereof;

FIG. 4 is a rear view thereof;

FIG. 5 is a right view thereof;

FIG. 6 is a top view thereof; and,

FIG. 7 is a bottom view thereof.

The broken lines shown in the drawings are for illustrative purposes only and form no part of the claimed design.
